STEAM GENERATOR

Filed Dec. 29, 1928

UNITED STATES PATENT OFFICE

WALTER J. WOHLENBERG, OF NEW HAVEN, CONNECTICUT, ASSIGNOR TO ERIE CITY IRON WORKS, OF ERIE, PENNSYLVANIA, A CORPORATION OF PENNSYLVANIA

STEAM GENERATOR

Application filed December 29, 1928. Serial No. 329,128.

The present invention is designed to improve a steam generator involving a boiler of the Stirling type and a connected water wall. It is desirable in an apparatus of this kind to provide for a free circulation in the boiler proper and also a circulation through the water walls which will not be disturbed by, or disturb materially the boiler circulation. One of the objects of the present invention is to accomplish this. The invention is further directed to simplifying the construction, making each of its elements capable of efficient operation, and so arranging the parts as to correct for variations in expansion and contraction. Features and details will appear from the specification and claims.

A preferred embodiment of the invention is illustrated in the accompanying drawings as follows:

20 Fig. 1 shows a section on the line 1—1 in Fig. 2.

Fig. 2 a front elevation of the generator.

1 marks the front upper drum, 2 the rear upper drum, 3 the lower drum, 4 front tubes connecting the drums 1 and 2, and 5 upper tubes connecting the drums 1 and 2, and 6 tubes connecting the drums 2 and 3. This is a typical three-drum boiler in which there is a circulation, the tubes 6 forming the down-flow tubes, the tubes 4 the up-flow tubes, and 5 the connecting steam and water tubes between the drums 1 and 2, the flow being from the front drum to the rear.

35 The water wall system for the furnace comprises tubes 7 in the side walls. These are preferably inwardly deflected at 7a giving to the lower part of the system a basket form leaving a space 7b for the discharge of ash.

40 The tubes 7 follow the line of the furnace wall, as indicated by dash lines and extend into an upper wall tube header 8. The wall tubes 7 terminate at their lower ends in a lower wall tube

45 header 9. The upper wall tube header has an up-flow header, or riser 10. This is connected by bent tubes 11 with the end of the rear drum, the tubes 11 extending radially and outwardly from the front face of the rear drum. A down-comer tube 12 leads to

the lower wall tube header 9 and terminates in a down-comer header 13. The header 13 is connected by bent tubes 14 with the end of the rear drum 2, these tubes 14 extending from the lower face of the rear drum, the headers 9 and 10 being arranged at an angle to each other so as to properly distribute these connecting tubes and further to facilitate a natural flow through them.

55 The wall system, just described, with the connecting headers and tubes is duplicated at both sides of the furnace. The position of the furnace walls is indicated by dotted lines and it will be noticed that the down-comer tubes are arranged without these walls so that there is no heat transfer to them to interfere with the down-flow of water through them. It will also be noticed that the rear drum is somewhat longer than the front drum so as to afford space for the connection of the tubes 11 and 14. It will be seen that the wall system is directly connected for its circulation through one drum and this drum is subjected to less fluctuation in water levels and steam agitation than the front drum. Consequently the levels effecting the wall system are maintained reasonably constant and it will be noted that the circulation in the boiler which passes through the rear drum follows through the drum to a large extent independently of the circulation of the wall system. On the other hand, the wall system passing to and from the drum affords a perfect release for any steam that

70 75 80 85 90 95 100

may be generated in the wall system and a complete circulation within each wall system without disturbing materially the main circuit of the boiler. The two systems, however, are completely tied together so that there is no possibility of a failure in either system so long as there is water in the generator as a whole.

It will be noted also that the down-comer tubes lead to the front ends of the header and the upper header discharges to the riser 10 at its front end. Thus there is a balanced resistance in total flow through each of the wall tubes 7 and in consequence a substantially equal flow through each of the tubes 7

so that all parts of the furnace wall are equally cooled.

What I claim as new is:—

1. In a steam generator, the combination of a boiler comprising a plurality of upper drums and boiler tubes included with said drums forming a circulating system; water tubes arranged in groups in planes at opposite ends of the drums; an upper and lower header for each of said groups, said headers being connected as headers with said groups of tubes; connecting headers arranged as risers from the upper headers; connections between the risers and the ends of the rear drum, said connections radiating from adjacent to the ends of said rear drum; down-comer headers; connections between the down-comer headers and the ends of said rear drum, said connections radiating from adjacent to the ends of said rear drum; and down-comer tubes leading from said down-comer headers to the lower headers.

2. In a steam generator, the combination of a boiler comprising a plurality of upper drums and boiler tubes included with said drums forming a circulating system; water tubes arranged in groups in planes at opposite ends of the drums; an upper and lower header for each of said groups, said headers being connected as headers with said groups of tubes; connecting headers arranged as risers from the upper headers; connections between the risers and the ends of the rear drum, said connections radiating from adjacent to the ends of said rear drum; down-comer headers; connections between the down-comer headers and the ends of said rear drum, said connections radiating from adjacent to the ends of said rear drum; and down-comer tubes leading from said down-comer headers to the lower headers, the down-comer tubes leading to the front ends of the lower headers and the risers leading from the rear ends of the upper headers.

3. In a steam generator, the combination of a boiler comprising a drum and boiler tubes included with said drum forming a circulating system; furnace wall tubes arranged in a group extending from one end of said drum; an upper header having a riser adjacent the end of said drum; tube connections between the riser and the end of the drum, said connections radiating from adjacent to the end of the drum; a lower header for the wall tubes, said lower header being connected as a header with said wall tubes; a down-comer header arranged at an angle to the riser and below the end of the drum; connections between the down-comer header and the end of the drum, said connections radiating from adjacent to the end of the drum; and a connection between the down-comer header and the lower header.

4. In a steam generator, the combination of a boiler comprising a drum and boiler tubes

included with said drum forming a circulating system; furnace wall tubes arranged in a group extending from one end of said drum; an upper header having a riser adjacent the end of said drum, said header being connected as a header with said wall tubes; tube connections between the riser and the end of the drum, said connections radiating from adjacent to the end of the drum; a lower header for the wall tubes; a down-comer header arranged at an angle to the riser and below the drum; connections between the down-comer header and the end of the drum, said connections radiating from adjacent to the end of the drum; and a connection between the down-comer header and the lower header, said last-mentioned connection extending to the opposite end of the lower header from that from which the riser extends from the upper header.

5. In a steam generator, the combination of a boiler comprising a drum and boiler tubes included with said drum forming a circulating system; furnace wall tubes arranged in a group extending from one end of said drum; an upper header having a riser adjacent the end of said drum, said header being connected as a header with said wall tubes; tube connections between the riser and the end of the drum, said tubes radiating adjacent to the end of the drum; a lower header for the wall tubes; a down-comer header arranged at an angle to the riser, said down-comer header being below the drum; connections between the down-comer header and the end of the drum, said connections radiating from adjacent to the end of the drum; and a connection between the down-comer header and the lower header, the connections between the down-comer header and the drum being in the form of curved tubes, the down-comer header being arranged outside of the end of the drum.

6. In a steam generator, the combination of a boiler comprising a drum and boiler tubes included with said drum forming a circulating system; furnace wall tubes arranged in a group extending from one end of said drum; an upper header having a riser adjacent the end of said drum, said header being connected as a header with said wall tubes; tube connections between the riser and the end of the drum, said tubes radiating adjacent to the end of the drum; a lower header for the wall tubes; a down-comer header arranged at an angle to the riser, said down-comer header being below the drum; connections between the down-comer header and the end of the drum; and a connection between the down-comer header and the lower header, the connections between the riser and down-comer header and the drum being in the form of curved tubes, said riser and down-comer header being outside of the end of the drum.

7. In a steam generator, the combination of a boiler comprising a plurality of upper drums and boiler tubes included with said drums forming a circulating system; furnace wall tubes arranged in groups in planes at the ends of the drums; upper and lower headers for said furnace wall tubes, said headers being connected as headers with said wall tubes; connecting headers in the form of 5 risers leading from said upper headers; connections in the form of bent tubes extending from the risers to the ends of the rear drum, said tubes radiating from the drum adjacent to its ends; down-comer headers arranged at 10 an angle to the risers and arranged below the drum; bent tubes connecting said down-comer headers and the ends of the rear drum, said tubes radiating from the drum adjacent to its ends; and down-comer tubes connecting 15 20 the down-comer headers with the lower headers.

8. In a boiler, the combination of an upper rear drum and tubes operating herewith and completing a circulating system; wall tubes 25 arranged in the plane of the end of the drum, said tubes being bent inwardly toward their lower end to form a floor for a furnace; headers for the lower and upper ends of said wall tubes, said headers being connected as headers 30 with said wall tubes; risers in continuation of the upper headers; tube connections between the risers and the upper rear drum, said connections radiating from adjacent to the ends of the rear drum; down-comer headers 35 below the risers; tube connections between the down-comer headers and the upper rear drums, said tube connections radiating from the rear drum in approximately the same plane as the connections leading to the 40 risers; and connections between the down-comer headers and the lower wall tube headers.

In testimony whereof I have hereunto set my hand.

45 WALTER J. WOHLENBERG.
